(57) **CLAIM**

The ornamental design for a portable electric power tool body, as shown and described.

DESCRIPTION

FIG. 1 is a rear, left and top perspective view of a portable electric power tool body showing our new design;

FIG. 2 is a rear and bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines in the drawings illustrate the environmental structures or portions of the portable electric power tool body which form no part of the claimed design. The dash-dot-dot lines represent the boundary of the claimed design and form no part of the claimed design.
